UNITED STATES PATENT OFFICE.

GEORGE WOOD, OF CLEVELAND, OHIO.

BODY-REST.

1,060,655.

Specification of Letters Patent.

Patented May 6, 1913.

Application filed July 17, 1912. Serial No. 709,870.

To all whom it may concern:

Be it known that I, GEORGE Wood, a citizen of the United States, and a resident of Cleveland, county of Cuyahoga, and State 5 of Ohio, have invented a new and useful Improvement in Body-Rests, of which the following is a specification, the principle of the invention being herein explained and the best mode in which I have contemplated 10 applying that principle, so as to distinguish it from other inventions.

The present invention relates generally to what may be termed body-rests, and its general object is the provision of a device which 15 may be placed on a bed or couch so that a person lying upon the bed or couch may rest the upper part of his body on the device. The supporting member proper of the device is capable of adjustment to different angles, 20 and the present invention provides such a device characterized by easy adjustment.

To the accomplishment of the foregoing and related objects, said invention, then, consists of the means hereinafter fully 25 described and particularly pointed out in the claims.

The annexed drawing and the following description set forth in detail certain mechanism embodying the invention, such 30 disclosed means constituting, however, but one of the various mechanical forms in which the principle of the invention may be used.

In said annexed drawing:—Figure 1 is a rear perspective view of a device embodying 35 the invention; Fig. 2 is a section taken on a plane between the spaced bars of the lazy-tong, and Fig. 3 is a section on the line A—A in Fig. 2.

The device comprises a base 1 formed by 40 a suitable frame-work, and hinged to the base at 2 are the side members 3 of a frame which comprises, with the side members, a top cross-piece. A flexible support 4, which is preferably formed of canvas, is secured 45 over the side members 3 of the frame, and suitably secured as by the lacing 5. Slotted bars 6 are removably fitted over the covered side and top members of the hinged frame and are held in place merely by friction, 50 the bars 6 giving the hinged support a more ornamental appearance.

Suitably secured at the outer end of the base is a transversely extending rod 7 provided at its opposite ends with stops 8, while 55 slidable on the rod are two blocks 9. Springs 10, disposed between the respective

blocks and stops, tend to prevent outward movement, or separation, of the blocks. Secured to the corresponding end of the hinged support is a transversely extending rod 11 60 provided at its outer ends with stops 12, while slidable on the rod are two blocks 13. Springs 14, disposed between the respective blocks and stops, and a spring 15 disposed between the two blocks 13, tend to restrain 65 outward movement, or separation, of the blocks.

A lazy-tong 16 has the free ends of its upper levers pivoted to the respective blocks 13, and the free ends of its lower levers pivoted to the respective blocks 9, and a spring 70 17, secured preferably to the joints of the levers, tends to extend the lazy-tong and is of sufficient force to normally hold the lazy-tong in its extended position.

Secured at one end to one of the blocks 9 75 is a transversely extending bar 18 which is provided at its free end with a plurality of teeth 19 which are adapted to selectively engage a pin 20 secured to the other block 9. Normally, the pin 20 is in engagement with 80 one of the teeth 19, and the teeth are so shaped that during such engagement the bar 18, which obviously is moved by movement of the lazy-tong, is free to allow extension 85 of the lazy-tong, but will prevent its contraction. A member 21 is pivoted to the base below the bar 18, and by pulling upon its outer end by a cord or chain 22 it will be rocked sufficiently to raise the bar 18 to disengage any of the teeth thereon from the pin 90 20, thus allowing further contraction of the lazy-tong with the consequent lowering of the hinged support.

In operation, the device is bodily placed 95 on a bed, for instance, and a person lying upon the bed may recline against the hinged support. Since the spring 17 normally holds the lazy-tong in full extended position, and since the pin 20 is normally in engagement with one of the teeth 19, the 100 hinged support will be secured in its uppermost position. If the user desires to lower the support, a slight pull on the cord 22 will disengage the engaging tooth from the pin 20, and the weight of the user's body, especially if a little pressure be exerted, will 105 lower the support to any desired position and upon the release of the cord 22 the pin 20 will engage another of the teeth 19 and secure the support from lowering beyond 110 that selected position. If, now, the user desires to again lower the support, he may do

so by pulling on the cord 22, but he may raise the support merely by raising his body, and in doing this he is aided by the force of the spring 17, the primary object of the 5 springs 10, 14 and 15 being to act as buffers during lowering of the support. If the user has adjusted the support to some position in which the lazy-tong is partially contracted, and wishes to secure the support in that position so that it will not rise therefrom, he may engage one of the hooks 25, carried by cord 24, onto a projection 23 secured to the hinged support.

The general object of the frame construction illustrated, especially in Fig. 3, is to provide a flexible body support which may be changed or removed when desired, and yet at the same time to make the support slightly when in use.

20 It is to be noted that the base 1 is composed of two side members joined at their outer ends by a cross member 26 with angular braces 27 extending from the member 26 to the side members near the ends at 25 which the supporting frame is hinged. Neither the base 1 nor the hinged support has any cross bar at the hinged end, or near the hinged end. This construction is important, for it allows the user to lower the 30 support until it is almost level, and the absence of cross bars not only makes possible the lowering to this extent, but also renders the device thoroughly comfortable in its lowest position. It is therefore unnecessary 35 when the user wishes to lie substantially flat on the bed to remove the body-rest from the bed.

Other modes of applying the principle of my invention may be employed instead of 40 the one explained, change being made as regards the mechanism herein disclosed provided the means stated by any of the following claims or the equivalent of such stated means be employed.

45 I therefore particularly point out and distinctly claim as my invention:—

1. In a device of the character described, the combination of a base; a support hinged to the base; an extensible member 50 disposed between the base and support; a spring tending to extend said member; means operable by movement of said member adapted in a plurality of positions of the member to restrain its contraction; and 55 means for releasing said restraining means.

2. In a device of the character described, the combination of a base; a support hinged to the base; an extensible member disposed between the base and support; a 60 spring tending to extend said member; a bar provided with a plurality of teeth; a projection, said bar and projection being relatively movable by movement of said member, said projection being normally in

engagement with one of said teeth and 65 adapted to restrain contraction of said member; and means for disengaging the tooth and projection.

3. In a device of the character described, the combination of a base; a support 70 hinged to the base; an extensible member disposed between the base and support; a spring tending to extend said member; a bar provided with a plurality of teeth, said 75 bar being movable by movement of said member; a projection normally engaging one of said teeth and adapted to restrain contraction, but not extension, of said member; and means for disengaging the tooth and projection.

4. In a device of the character described, the combination of a base; a support hinged to the base; a lazy-tong slidably connected at its opposite ends to the support and the base; a spring tending to extend said lazy-tong; a bar secured to said lazy-tong and movable by movement of the lazy-tong, said bar being provided with a plurality of teeth; a projection normally engaging one of said teeth and adapted to restrain contraction, but not extension, of said 80 lazy-tong; and means for disengaging the tooth and projection.

5. In a device of the character described, the combination of a base; a support 95 hinged at one end to the base; a transverse rod secured to the support near the opposite end; a second transverse rod secured to the base near its corresponding end; two blocks slidable on the first rod; two blocks slidable on the second rod; a lazy-tong secured at its ends to said blocks; a spring tending to extend said lazy-tong; a bar pivoted at one end to one of the blocks on the second rod and provided near its opposite end with a 100 plurality of teeth; a pin secured to the other block on the second rod and normally engaging one of said teeth and adapted to restrain contraction, but not extension, of said lazy-tong; and a trip adapted to raise 105 said bar to disengage said tooth and said pin.

6. In a device of the character described, the combination of a base; a support hinged at one end to the base; a transverse 115 rod secured to the support near the opposite end and provided at its ends with stops; a second transverse rod secured to the base near its corresponding end and provided at its ends with stops; two blocks slidable on the first rod; springs disposed between said blocks and between the blocks and stops and tending to restrain separation of said blocks; two blocks slidable on the second rod; springs disposed between the respective blocks and stops and tending to restrain separation of said blocks; a lazy-tong secured at its ends to said blocks; a spring 120

tending to extend said lazy-tong; a bar pivoted at one end to one of the blocks on the second rod and provided near its opposite end with a plurality of teeth; a pin secured 5 to the other block on the second rod and normally engaging one of said teeth and adapted to restrain contraction, but not extension, of said lazy-tong; and a trip adapt-

ed to raise said bar to disengage said tooth and said pin. 10

Signed by me this 11th day of July, 1912.

GEORGE WOOD.
